UNITED STATES PATENT OFFICE.

WILLIAM M. SCHOLL, OF CHICAGO, ILLINOIS.

CUSHION-HEEL FOR SHOES.

1,174,620.

Specification of Letters Patent. Patented Mar. 7, 1916.

Application filed May 29, 1915. Serial No. 31,136.

To all whom it may concern:

Be it known that I, WILLIAM M. SCHOLL, a citizen of the United States, residing at Chicago, in the county of Cook and State of Illinois, have invented certain new and useful Improvements in Cushion-Heels for Shoes, of which the following is a specification.

My invention relates to improvements in cushion heels for shoes, and has among its objects to provide a heel the cushioning effect of which is modified, in a localized area, for decreased resiliency, and the surface of which is preferably modified for increased frictional qualities.

In the drawings wherein I have illustrated an embodiment of my invention Figure 1 is a side elevation of a fragment of a shoe, showing my heel attached thereto. Fig. 2 is a bottom elevation thereof; Fig. 3 is a section on line 3—3 of Fig. 2; Fig. 4 is a detail of a post.

10 indicates in general a shoe, of which 11 is the heel-base of leather, usually composed of several lifts, to which the cushion heel element or lift is to be applied. The cushioning heel structure generally indicated by the numeral 12, consists of a rubber body 13 nailed or otherwise secured to the heel foundation and constituting the tread surface of the shoe heel.

While the resiliency of the rubber heel greatly promotes the comfort of the wearer, by lessening shock of impacts, giving a springy tread, and the like, it is not without harmful tendency, particularly in the instance of persons who are afflicted with fallen-arch or flat-foot-tendency, or who wear corrective appliances or instep arch supports for prevention or correction of such ailments. The heel portion of the rubber-heeled shoe, yielding as an entirety, tends to permit shifting strains to be thrown upon the foot of the wearer that enhance the tendency of the bones to spread, and the usual all-resilient heel-element affords no relatively unyielding (as compared with the rubber) foundation upon which the instep-arch-support may find adequate bearing.

50 In the embodiment of my invention I provide in the rubber heel body 13 an embedded strut or post 14, preferably made of leather, preferably extending through and through the rubber for exposure on both surfaces thereof. Such post I locate, preferably, at the inner forward portion of the heel ele-

ment, so that it underlies the forward inner portion of the os-calci, and whereon the ordinary arch support (suggestively illustrated in dotted lines at A,) rests at its rear end. Thus the embedded leather post 14 form substantially a continuation of the stiff leather foundation structure to a localized portion of the heel element taking from it much of its elasticity as well as varying the constituent of its wearing surface.

In mechanical construction I prefer to make the leather post oval, and to provide it with a groove 15 extending around its periphery, whereby when such post is embedded in the rubber, it is firmly held against displacement.

It will be apparent to those skilled in the art that, since the leather has frictional qualities different from those of the rubber, and tends to hold frictionally in some situations where rubber will slip (as upon wet stone, and the like) my improved construction gives to the heel advantageous anti-slipping qualities, as well as its advantageous localized stiffness.

While I have herein described in some detail a particular embodiment of my invention it will be apparent to those skilled in the art that changes might be made in the details thereof without departure from the spirit of my invention and within the scope of the appended claims.

Having described my invention, what I claim is:

1. A cushion-heel element having localized comparative-rigidity and general comparative-resiliency, comprising a relatively resilient body and relatively rigid means incorporated in the body, said means wholly local to an area at the front, inner portion thereof.

2. A cushion-heel element having localized comparative-rigidity and general comparative-resiliency, comprising a body and a relatively rigid structure incorporated in the body extending therethrough from face to face and wholly local to an area at the front inner portion of the body, the body encompassing said means being of rubber and of substantially uniform, relatively-great resiliency.

3. A cushion-heel element for shoes comprising a leather post of substantially the full depth of said element, constituting the portion of said element at the forward inner part thereof, and a body of rubber, of sub-

stantially uniform depth and resiliency encompassing said post, whereby the relative stiffness of the post is local to a relatively small area of the entire element.

5 4. In a cushion-heel element, the combination of a rubber body and a single post of material less resilient than the rubber embedded in said rubber body, said post extending through the body vertically from 10 face to face of the rubber for contact with the shoe heel foundation with the ground, said post local to a relatively small area at the front inner portion of the element.

5 5. A cushion-heel element, having the forward inner portion thereof formed of a non-resilient material giving substantially rigid support at such area, the remainder of said

element being of a resilient material of substantially uniform compressibility throughout.

6. A shoe heel element comprising a relatively rigid portion local to the forward inner part of the element and extending clear through the same, and an encompassing body portion that is all of greater resiliency than the relatively rigid portion. 20 25

In testimony whereof I hereunto set my hand in the presence of two subscribing witnesses.

WILLIAM M. SCHOLL.
